DESIGN FOR A BATTERY HOLDER

Raymond C. Casanov, Chicago, Ill.

Application July 16, 1943, Serial No. 110,674

Term of patent 7 years

To all whom it may concern:

Be it known that I, Raymond C. Casanov, a citizen of the United States and a resident of Chicago, in the county of Cook and State of Illinois, have invented a new, original, and ornamental Design for a Battery Holder, of which the following is a specification, reference being had to the accompanying drawing, forming a part thereof, and in which:

Fig. 1 is a top plan view of a battery holder showing my new design;

Fig. 2 is a perspective view;

Fig. 3 is a front elevational view; and

Fig. 4 is a bottom plan view of the same.

I claim:

The ornamental design for a battery holder, as shown.

RAYMOND C. CASANOV.
